Company, Philadelphia, Pa., a corporation of
Pennsylvania

Application January 28, 1932, Serial No. 589,379

5 Claims. (Cl. 8--19)

The present invention relates to dyeing or material treating machines using solutions and more particularly to a solution holding tank structure.

In the treating of skeins of yarn or material and particularly as regards dyeing it is essential that the dye liquor be not only uniformly mixed but remain so throughout the process of treating or dyeing. The type of machine which suspends hanks of yarn from a pole or other support above a tank of dye solution and sprays or otherwise saturates the yarn so that the dye flows downward over the material and falls back into the tank is particularly susceptible to variation of the dye solution. This is because the solution drops from the lower end of the material and if the material is too far above the level of the tank liquid the falling solution will break up into drops and each drop become surrounded by air which is then carried down into the main body of the solution. This air disturbs the uniformity of the dye solution and a recirculation of this air impregnated solution will cause streaking and imperfect dyeing results.

Some of the objects of the present invention are to provide an improved tank for dye or other material treating solutions; to provide a device wherein it is possible to maintain a constant distance between the suspended ends of material and the level of the liquid in the tank; to provide a mechanism for creating a false liquid level whereby the fall distance of liquid is constant regardless of the length of suspended hanks; to provide means for adjusting the level of a treating liquid to conform to the material to be treated; and to provide other improvements as will hereinafter appear.

In the accompanying drawing Fig. 1 represents a sectional elevation of the skein support and tank of a circulating dyeing machine embodying one form of the present invention; Fig. 2 represents a plan of the tank and associated parts of the invention; and Fig. 3 represents a section on line 3--3 of Fig. 1.

Referring to the drawing one form of the present invention is shown as incorporated in a dyeing machine of the type having a tank 10 for dye or other treating liquid 11 and an overhead perforated support 12. The supports 12 suspend skeins of yarn 13 or other material to be treated above the level of the liquid in the tank 10 and with the lower ends of the skeins spaced from the normal level of the liquid. A pump (not shown) together with suitable piping to the support 12 circulates and recirculates the dye liquid 55 to the suspended skeins so that the latter substan-

tially ride in a film of issuing liquid and are covered by it as it flows downward over the skeins to drop back into the body of liquid in the tank. The quantity of liquid in the tank 10 is such as to maintain a substantially constant level 60 therein and this level bears a definite relation to the length of the suspended skeins. In other words the distance from the lower ends of the skeins to the liquid level is such that the returning liquid leaves the skeins and enters the tank 65 liquid in an unbroken stream. That this may take place with certainty this distance is predetermined for skeins of standard length and remains unchanged regardless of using skeins which are shorter than standard. With this last length of 70 skeins the distance from the skein ends to the liquid level is so increased that the liquid instead of falling as a returning stream to the tank is broken up into drops and hence each carries an envelope of air into the tank liquid. The result 75 of this is a deleterious oxidation which makes itself apparent in the product by streaks and non-uniform dyeing.

For the purpose of overcoming the disadvantage above pointed out and in effect transforming 80 the machine into a universal one in so far as variation of skein length is concerned a trough 14 is provided consisting of side hanger arms 15 having upper hook ends 16 for respectively seating upon the side rims 17 of the tank 10. These 85 arms 15 depend into the tank 10 and carry the trough of concave form which serves to provide a supplemental liquid pool 18 which is susceptible of vertical adjustment in order that the distance from the lower ends of the skeins to the liquid 90 level will always be the required minimum to prevent the falling liquid from breaking up into particles before reaching the tank liquid. As here shown the two discharge slots 20 for liquid 95 are provided at opposite parts of the trough by cutting away the material and bending it downward in the form of guide flanges 21 to direct the overflow from the supplemental pool of liquid into the main body of liquid.

Adjustment of the trough 14 is made possible 100 by a slot and bolt construction consisting of slots 22 in the arms 15 and bolts 23 passing through apertured upward side extensions 24 of the trough 14. Thus by lowering the bolts 23 105 the trough 14 can be brought to any desired level with respect to the suspended material and then clamping the parts by tightening the bolts 23. Instead therefore of the machine being limited to 110 a dyer for skeins of one length only it becomes a

machine capable of successfully dyeing uniformly skeins of various lengths.

In describing the operation of the machine of the present invention it will be assumed that 5 skeins having a length less than standard length are to be dyed. Under such circumstances the trough 14 is attached in operative position within the tank 10 and the skeins hung in position for dyeing upon the support 12. The bolts 23 are 10 now loosened and the trough 14 brought to the position where the supplemental liquid level therein is spaced from the ends of the skeins the predetermined distance for return of the liquid without breaking it up into drops or producing such 15 splashing as will bring about the above mentioned harmful oxidation. When properly placed the bolts 23 are tightened and the trough 14 remains at the new level until there is a change of material length at which time it is again shifted to 20 give the correct spacing from the lower end of the material. In the foregoing the term "skein" is used only by way of example to explain one use of the machine and it is to be understood that the invention broadly comprehends the dyeing of 25 piece goods or any other material.

While only a single form is shown in which this invention may be embodied, it is to be understood that the invention is not limited to any specific construction, but might be applied to various 30 forms without departing from the spirit of the invention or the scope of the appended claims.

Having thus described our invention, we claim:

1. In a dyeing machine, the combination of a 35 tank for holding a treating liquid, a support for suspending material above the liquid in said tank, and means for establishing a different liquid level in said tank while maintaining the normal level constant, whereby loops of material of different length can be suspended from said support with 40

the lower ends thereof spaced the same distance from said liquid.

2. In a dyeing machine, the combination of a tank for holding a treating liquid, a fixed support for suspending material above the liquid in said tank, said support having perforations to deliver 80 treating liquid to said material, and means for establishing an auxiliary pool of liquid above the level of the main body of liquid in said tank.

3. In a dyeing machine, the combination of a tank for holding a treating liquid, a support for suspending material above the liquid in said tank, means for establishing an auxiliary pool of liquid above the level of the main body of liquid, and means for varying the distance between the two 85 liquid levels.

4. In a dyeing machine, the combination of a tank for holding a treating liquid, a support for suspending material above the liquid in said tank, a trough provided with an overflow located in said tank between the level of the liquid and the suspended end or ends of said material, and means for adjusting said trough vertically to maintain a predetermined distance between said material and said trough. 95

5. In a dyeing machine, the combination of a tank for holding a treating liquid, a support for suspending material above the liquid in said tank, hanger arms arranged to engage the sides of said tank and hang within said tank, a trough having 105 a depressed portion to form a supplemental body of liquid, means forming an overflow from said trough, and adjustable connections between said trough and said arms whereby said trough can be located a predetermined distance from the suspended end of said material. 110
